United States Patent Office

Des. 196,589
Patented Oct. 15, 1963

196,589

DRAWER FRONT OR SIMILAR ARTICLE

Melbourne F. Smith, Lenoir, N.C., assignor to Broyhill
Furniture Factories, Lenoir, N.C., a partnership

Filed Oct. 12, 1962, Ser. No. 72,094

Term of patent 14 years

(Cl. D33—1)

Fig-1

The back of the drawer front or similar article is conventionally plain.

I claim:

The ornamental design for a drawer front or similar article, as shown and described.
